METAL SASH AND METHOD OF MAKING SAME

Filed Feb. 14, 1930

UNITED STATES PATENT OFFICE

DANIEL CARLOUGH, OF CLIFTON, NEW JERSEY

METAL SASH AND METHOD OF MAKING SAME

Application filed February 14, 1930. Serial No. 428,334.

This invention relates to metal frames, as the metal frames for window sash and the like, and its object is to provide a joint between the frame rails where portions of the frame cross or meet each other which shall be of such construction that while the joint is exceedingly strong it requires but simple operations both to form the parts necessary thereto and to establish the joint.

10 In the drawings:

Fig. 1 shows a joint-including fragment of a frame embodying my invention in section on line 1—1, Fig. 4;

Fig. 2 is a similar view, with what I term 15 the abutting rails separated from what I term the through-rail;

Fig. 3 is a section on line 3—3, Fig. 2; and

Fig. 4 is a section on line 4—4, Fig. 1 before certain gibs are applied.

20 1 is the through-rail and 2 designates the abutting rails arranged one on each side of and each in a line intersecting that of the through-rail. In the example each of the rails is angular (T-shaped) in cross-section, 25 they are all of the same cross-sectional dimensions, and they are all arranged with their bases (corresponding to the heads of the T's) in the same plane. However, in all aspects of the invention these matters are not indispensable; nor is it indispensable in all aspects 30 that there be two of the abutting rails.

Each abutting rail 2 has a tongue 3 extending longitudinally from and integral with its upright wall or web 2a, which tongue is 35 preferably flat. Further, where as in the example there are two abutting rails, one on each side of the through-rail, the tongues thereof are preferably offset in opposite directions with respect to their webs 2a, as by the 40 reverse bends at 3a, so that the said webs will then lie in the same plane (Figs. 3 and 4). The end of each abutting rail is to abut the through-rail 1 when the joint is established, preferably both sides of (in Figs. 1 and 2, 45 above and below) its tongue, and if, as here, said rail 1 is T-shaped in cross-section this is accomplished by forming said end with an abutting end face 4 on the base 2b of such rail which is set back relatively to the end 50 face 5 on the web 2a and located at the rela-

tively opposite side of the tongue. Each tongue further has an opening here in the form of a slot 6 therein which is here V-shaped; each slot corresponds with the other in form and relative position.

The web 1a of the through-rail has an aperture 7 of such form as to admit both tongues snugly.

Each tongue being entered into aperture 7 until the end of the corresponding rail 2 abuts rail 1, which when both tongues are so entered will bring their slots into coincidence with each other, a gib 8 is driven into the slot at the side of rail 1 from which said tongue now protrudes. This gib is tapering and, while its taper may act to draw the corresponding rail 2 up firmly against rail 1 when the gib is entered, the taper serves to definitely limit the entering thereof. One edge of the gib lies face to face against the web of rail 1, and if at least the smaller end thereof, but preferably both ends, are bent off toward that side of the slot 6 which forms an acute angle with the adjoining face of web 1a of rail 1 the gib will not only be held in place but this bending thereof will cause it to wipe with pressure upon said face of web 1a and augment any pressure of the end of the corresponding rail 2 with rail 1 which was obtained in the first instance by driving in the gib.

The invention avoids any special forming of the rails beyond providing a slotted tongue on the abutting rail and an aperture in the through-rail and employing a mere tapering gib as a locking device and it further makes it possible to assemble the parts with facility and without the use of special tools.

So far as I am aware it is new in the art to provide a metal frame, of the class in which a rail abuts one side of a through-rail and has a portion thereof protruding through the through-rail and having an opening at its other side, with a gib held in said opening and having at least one end portion protruding therefrom and bent off toward and thereby jammed against said other side of the through-member; and I so claim broadly.

The method of securing to an apertured through-rail another rail angularly related

- to and abutting one side of the through-rail and having a portion thereof protruding through the through-rail and at its other side having an opening is also new which consists
 5 in securing a gib in the opening, causing the gib to contact only at its end portion with the through-rail, and straining the gib into jamming relation to the through-rail while so secured and contacting with the through-rail.
 10 Having thus fully described my invention what I claim is:
 15 1. A metal frame including an apertured through-rail, another rail angularly related to and abutting one side of the through-rail and having a portion thereof protruding through the aperture of said through-rail and having an opening at the other side thereof, and a gib held in said opening and having one end portion thereof bent off toward and
 20 thereby jammed against said other side of the through-rail.
 2. A metal frame including an apertured through-rail another rail angularly related to and abutting one side of the through-rail and having a portion thereof protruding through the aperture of said through-rail and having an opening at the other side thereof, and a gib held in said opening against turning on its own longitudinal axis and bent
 25 off toward and having a surface lateral of the plane of bending thereof thereby jammed against said other side of the through-rail.
 3. The method of securing to an apertured through-rail another rail angularly related to and abutting one side of the through-rail and having a portion thereof protruding through said through-rail and at the other side thereof having an opening, which consists in first securing a gib in said opening
 30 against turning on its own longitudinal axis and while they are so secured bending off an end-portion of the gib into jamming relation to said other side of the through-rail.
 4. The method of securing to an apertured through-rail another rail angularly related to and abutting one side of the through-rail and having a portion thereof protruding through said through-rail and at the other side thereof having an opening, which consists in first securing a gib in said opening
 35 against turning on its own longitudinal axis and while they are so secured bending off an end portion of the gib in a plane forming an acute angle with said other side of the through-rail and into jamming relation thereto.
 5. The method of securing to an apertured through-rail another rail angularly related to and abutting one side of the through-rail and having a portion thereof protruding through said through-rail and at the other side thereof having a gib-receiving opening formed to confine that portion of a flat gib which is immediately received thereby in a plane forming an acute angle with a surface

portion of said other side, inserting a flat gib in said opening and finally bending off an end portion of the gib into jamming relation to said surface portion.

6. The method of securing to an apertured through-rail other rails angularly related thereto and abutting opposite sides of the through-rail and protruding through the through-rail and having coinciding openings each side of the through-rail, which consists in first securing gibs in said openings of both said other rails and one at each side of the through-rail and each against turning on its own longitudinal axis and while they are so secured bending off end portions of the two gibs into jamming relation to the respective sides of the through-rail.

7. A metal frame including an apertured through-rail, other rails angularly related to and having webs in substantially the same plane, each web having a tongue integrally connected therewith and protruding through the aperture of the through-rail and bent out of the plane of the web and overlapping the other tongue, and means to secure the protruding portion of each tongue against withdrawal from said aperture.

8. The method of securing to an apertured through-rail another rail angularly related to and abutting one side of the through-rail and having a portion thereof protruding through said through-rail and at the other side thereof having an opening which consists in securing a gib in the opening, causing the gib to contact only at its end portion with the through-rail, and straining the gib into jamming relation to the through-rail while so secured and contacting with the through-rail.

9. The method of securing to an apertured through-rail another rail angularly related to and abutting one side of the through-rail and having a portion thereof protruding through said through-rail and at the other side thereof having an opening which consists in securing a gib in the opening against turning on its own longitudinal axis, causing the gib to contact with the through-rail at a point out of alignment with the opening, and straining the gib into jamming relation to the through-rail while so secured and contacting with the through-rail.

In testimony whereof I affix my signature.
 DANIEL CARLOUGH.
